AIR-CURRENT ATTACHMENT FOR HEATING RADIATORS

Clarence M. Woolley, New York, N. Y., assignor to American Radiator Company, New York, N. Y., a corporation of New Jersey

Application September 26, 1935, Serial No. 42,235

5 Claims. (Cl. 261—137)

My invention relates to air-current attachments for heating radiators.

More particularly, embodiments of my invention are designed for assembly with heating radiators by direct support upon the heating radiator, securement being preferably had by hook-like elements or equivalent embracing a portion of the radiator assembly.

Preferred embodiments of my present invention comprise a housing enclosing and supporting one or more motor and fan assemblies, a septum provided with an opening or openings correlated respectively with such fan or fans, and ingress openings in the housing communicating with the interior of the housing above such septum.

Commercial embodiments of my invention comprise the stated essential elements combined as a unitary assembly, thus affording pre-fabricating and assembly in a factory or the like, and facilitating installation relative to a radiator, removal of the assembly as a unit for inspection, cleaning and repair, etc. Desirably, such unitary assemblies may be of standard lengths of casing, the number of the motor-fan units being determined by the size of the casing and the motor-fan unit output.

During the stage of operation of the fan, assuming steam or other suitable heating medium to be supplied to the radiator, air is projected downwardly and in heat exchange relation with the heating surfaces of the radiator, thus increasing the effective heat units delivered by the radiator, the air projected by the fan or fans being induced through the air ingress openings of the casing and bringing about the positive circulation, additionally to rise of temperature, of the air of the room or other space served by the radiator.

Further features and objects of the invention will be more fully understood from the following detail description and the accompanying drawing, in which—

Fig. 1 is a side elevation, partly broken away in vertical section for the sake of clarity, of a preferred form of a preferred embodiment of my invention.

Fig. 2 is a sectional view on line 2—2 of Fig. 1.

Referring to the preferred embodiment shown in Figs. 1 and 2, the illustrated type of my invention comprises a casing 10 having a substantially fully open bottom 11, members such as the angle plates 12, 12, respectively having one angled portion, see 12a, welded or otherwise secured to the material of the opposite sides 13, 14, of the casing

10, the projecting angled portions, see 12b, serving to rest upon aligned top face portions of the heating radiator assembly, R, usually of sections as shown in the drawing. By such or equivalent provision of means, the casing 10 is arranged to engage and be supported by such engagement with the upper face portions of a radiator assembly.

If desired, stability of support of the casing 10 is had by lowerly extending the opposite sides 13, 14, of the casing 10, as is indicated at 13a, 14a. Also, hook-like members, see 15, adjustably secured and carried at their fixed ends, see 15a, as by means of nut and threading, may be employed, as appears more fully hereinafter, for anchoring 15 the casing relative to the radiator assembly R.

One or more motor and fan assemblies may be utilized, the illustrated embodiment of Figs. 1 and 2 showing two such assemblies, each motor being indicated 16 and its associated fan 17. Such 20 motor-fan assembly is suitably housed within and supported by the casing 10, as by means of a bracket 18, one angled portion 18a of which may be secured by bolt and nut, or equivalent, to, say, the inner face of the rear side 13 of the casing 25 or housing 10. Preferably, each motor-fan assembly is resiliently suspended, conveniently had by suspending elements 19, 19, desirably of one length of resilient steel or other suitable metal or other material, suitably bent, and riveted or otherwise suspended from the free angled portion of its associated bracket 18.

Coordinated with such fan 17 I provide a septum 20 extending imperforately end to end within the casing or housing 10 from one lateral 35 side 13 to the opposite lateral side 14 excepting the one or more openings 20a, corresponding to the number of fans, which opening 20a each has a diameter slightly larger than the effective diameter of the therewith coordinated fan. If desired, 40 the edge of each opening 20a may be provided with a cylindrically extending flange, serving in coordination with the blades of the associated fan to form a "tunnel" for the projected circulation therethrough of air.

Ingress openings for air are shown in the illustrated preferred embodiment at 21, in this instance disposed wholly in one lateral side, i. e., the front side 14 of the casing, the remaining sides of the casing 10, i. e. its top 22, its opposite 50 end sides 23, 24, and its rear side 13 being imperforate; each of such air-ingress openings 21 is effectively located above the septum 20. However, if desired, air ingress openings may be provided in the material of more than one side, such 55

air ingress openings, instanced by the illustrated air ingress openings 21, communicating with the interior of the casing or housing 10 on the side of the septum in proper coordination with the 5 one or more fans 17.

Such one or more motors 16 may be of any suitable type. Advantageously, the motors are of electrical type.

As appears from the above, upon actuation of 10 the one or more motors 16, and therewith of the one or more fans 17, air is projected downwardly through the respective openings 20a of the septum 20 in heat exchange relation with the heating surfaces of the radiator assembly R, a suitable heating medium being assumed to be supplied to the radiator assembly.

The material of such septum 20 may afford, as shown, dual functioning, i. e., for the anchoring and adjustable positioning of the securing hooks 20 15, 15, in addition to its above stated purposes. Preferably, also, as shown, the septum 20 is spaced a predetermined clearance from the heating surfaces of the radiator assembly, as by means of spacers, see 25, conveniently of U-bent plates, the base of the U-formation engaging the flat under face of the septum 20 and embracing the body portion of the associated hook-like member 15, the free edges of the U-formation being usually rectilinear to rest upon usually 30 aligned top faces of the radiator assembly, or configurated in correspondence to the configuration of the top faces of the radiator assembly.

Embodiments of my invention find particular application as boosters of comfort in association 35 with conventional radiators of approved present and prior art practice, as for example in rooms and other spaces of a house or other structure of habitation, where enhancement of comfort is desirable or desired by reason of otherwise insufficient radiating surface of the installed radiator, or under conditions of unfavorable wind or other unfavorable outer atmospheric condition, or desirability of increased temperature for temporary periods as when bathing or on other 40 occasions, usually of intermittent character.

The period of actuation of the one or more motor-fan assemblies may be controlled by a manually operated switch, diagrammatically indicated at 26, which may provide for multiple 45 speed actuation. Advantageously, such current controlling switch 26 may be thermostatically responsive, most advantageously responsive thermostatically to differential temperature setting, as for example, providing for full speed of each 50 motor-fan assembly for a set minimum temperature, half or other partial speed for a set intermediate temperature, and "off" for a set maximum temperature.

Under the stages of operation of the fan assembly of my attachment to a heating radiator, air induced through the ingress openings is projected downwardly upon and in heat exchange relation to the heating surfaces of the radiator assembly, and generally toward the floor of the 55 room or other space served by the radiator. The greater the speed of any given fan assembly the more effectively the thus heated air is projected to such floor, thus correspondingly enhancing, i. e., boosting the comfort of person or persons desiring such objective. In all such stages of fan 60 operation the air of the room or other space is re-circulated as well as increased in temperature, in which function the air openings are advantageously in the front side of the casing.

Under the stage of non-operation of the fan

assembly, under the condition of supply of the heating medium to the radiator assembly, convection, i. e., gravity, heated air currents pass upwardly of the radiator assembly, thence between the usual spacings at the top of the radiator assembly or through the fan opening or openings and ultimately through the air openings 5 21 into the room or other space.

The resilient mounting of the motor and fan assembly serves to minimize mechanical transmission of vibration to the casing proper, and silence otherwise, incident to the actuation of the motor and of the fan, also to minimize mechanical shock or stresses to the motor or fan incident to handling of the assembly, etc. 10 15

By covering and/or enclosing the top of the radiator assembly, my invention serves to conceal the radiator assembly, which objective may be further attained by extending the front side of the casing to extend forwardly of or in front 20 of the radiator assembly to such extent as may be desired.

Whereas I have described my invention by reference to specific forms thereof, it will be understood that many changes and modifications may 25 be made without departing from the spirit of the invention.

I claim:

1. The combination with a radiator assembly, of a casing, one or more motor and fan assemblies housed within said casing, means supporting said one or more motor and fan assemblies and wholly supported by said casing, a septum provided with an opening or openings correlated with the fan or fans of said motor and fan assembly, said casing being provided with openings communicating with the interior of the casing above said septum, the bottom of the casing being substantially wholly open, and means carried by said casing for supporting said casing and its 30 stated associated elements wholly upon the upper face portions of the radiator assembly. 35 40

2. The combination with a radiator assembly, of a casing, one or more motor and fan assemblies housed within said casing, resilient means 45 supporting said one or more motor and fan assemblies and wholly supported by said casing, a septum provided with an opening or openings correlated with the fan or fans of said motor and fan assembly, said casing being provided with openings communicating with the interior of the casing above said septum, the bottom of the casing being substantially wholly open, means carried by said casing for supporting said casing and its stated associated elements wholly upon the 50 upper face portions of the radiator assembly, and disconnectible means for stationarily securing said casing to the radiator assembly. 55

3. The combination with a radiator assembly, of a casing, one or more motor and fan assemblies housed within said casing, means supporting said 60 one or more motor and fan assemblies and wholly supported by said casing, a septum provided with an opening or openings correlated with the fan or fans of said motor and fan assembly, said casing being provided at one lateral side only with openings communicating with the interior of the casing above said septum, the top of the casing being imperforate the bottom of the casing being substantially wholly open, and means carried by 65 70 said casing for supporting said casing and its stated associated elements wholly upon the upper fact portions of the radiator assembly, said casing supporting means including a lowerly edge extension of said one lateral side, said lowerly edge ex- 75

tension of said one lateral side being imperforate.

4. The combination with a radiator assembly, of a casing, one or more motor and fan assemblies housed within said casing, means supporting said one or more motor and fan assemblies and wholly supported by said casing, a septum provided with an opening or openings correlated with the fan or fans of said motor and fan assembly, said casing being provided at its front side only with 10 openings communicating with the interior of the casing above said septum, the bottom of the casing being substantially wholly open, and means carried by said casing for supporting said casing and its stated associated elements wholly upon 15 the upper face portions of the radiator assembly, said casing supporting means including a lowerly edge extension of said front side, said lowerly edge extension of said front side being imperforate.

5. The combination with a radiator assembly, of a casing, one or more motor and fan assemblies housed within said casing, means supporting said one or more motor and fan assemblies and wholly supported by said casing, a septum provided with 5 an opening or openings correlated with the fan or fans of said motor and fan assembly, said septum otherwise extending imperforately wholly through the interior of the casing, said casing being provided with openings communicating 10 with the interior of the casing above said septum, the bottom of the casing being substantially wholly open, and means carried by said casing for supporting said casing and its stated associated elements wholly upon the upper face portions of 15 the radiator assembly.

CLARENCE M. WOOLLEY.
